UNITED STATES PATENT OFFICE.

EDWIN R. BRYANT, OF ROCHESTER, NEW YORK, ASSIGNOR TO THE ROCHESTER MACHINE TOOL WORKS, (LIMITED,) OF SAME PLACE.

ATTACHMENT FOR METAL-PLANERS.

SPECIFICATION forming part of Letters Patent No. 296,270, dated April 1, 1884.

Application filed August 27, 1883. (No model.)

To all whom it may concern:

Be it known that I, EDWIN R. BRYANT, of Rochester, in the county of Monroe and State of New York, have invented a new and useful Improvement in Attachments for Iron-Planers, which improvement is fully set forth in the following specification and accompanying drawings.

Much practical difficulty is experienced by machinists in planing the under surfaces of work with the iron-planers as ordinarily constructed, crooked and awkward-shaped tools having to be provided for the purpose, which, on account of their shape and length, spring away from the work when the cut being taken is at all heavy, and the use of which tools is attended with other disadvantages and inconveniences.

To produce a simple attachment for such a planer, designed to hold a simple cutting-tool rigidly in position to plane under-surfaces and provide the same with certain features of adjustment and other desirable capabilities, is the object of my present invention.

Referring to the drawings, Figure 1 is a front elevation of my improved attachment, shown as secured to the apron of the planer by means of the tool-clamping bolts of the same, showing the tool in position to operate; Fig. 2, a top view of the same, looking in the direction indicated by arrow *z* in Fig. 1, some of the parts being shown in different position; and Fig. 3, a side elevation of the same, viewed as indicated by arrow *y* in Fig. 1.

Referring to the parts, *A* is the swinging slide, and *B* the apron, of an iron-planer, as commonly constructed, and *C* the taper bolt, holding the apron in place against the slide *A*. The swinging slide is constructed to swing 40 in a vertical plane upon the cross-slide (not shown) in the usual manner.

F are the usual tool-clamping bolts, extending horizontally out from the face of the apron.

G is a block of iron, forming the body of my improved attachment, which I attach directly or indirectly to the swinging slide *A*, so that it shall partake of the various motions of said slide. This block or body may be made a separate piece from the apron and secured

thereto by means of the clamping-bolts for 50 holding the tool, or it may be made in one piece with the apron and secured to the vertical slide *A*, by means of the taper bolt *C*, between the projecting sides *D*, a separate apron of usual construction for holding the cutting-tools being also provided for the planer. I prefer, however, the form as shown, in which the body is provided with holes adapted to slip over the clamping-bolts *F* of the apron, the ordinary clamp for the tools having been 60 first removed, the back surface of the body, when in place, resting against the face *e* of the apron. The clamping-nuts *I* bear against seats *e*, formed on the face of the body *G*, which holds the body rigidly to the apron and indirectly to the swinging slide. The body *G* is provided with a longitudinal opening, into which is fitted a tool stock or shaft, *K*, provided at its lower end with an opening in which to receive a cutting-tool, *b*, all being 70 clearly shown in Fig. 1. The upper part of the body is cut away, forming a cavity, *g*, in which is fitted a circular plate, *H*. The tool-stock pierces the plate *H* at its center, as shown in Fig. 2, and these two parts are connected, so as to turn together, by means of a key or feather, *a*, secured to the plate in a slot, *f*, in position to slide in a longitudinal race, *d*, of the tool-stock. A set-screw, *u*, passing horizontally through the plate and so pressing against the key *a*, holds the plate and tool-stock rigidly together; but when thus held they may turn a short distance on their bearings within and upon the body *G*, as will be fully explained further on. By 85 loosening the set-screw *u* the tool-stock may be longitudinally adjusted within the body and plate *H*, for the purpose of bringing the tool to the work. The plate has an extended part, *k*, the ends or faces *n* *n'* of which are 90 arranged to meet the respective faces, *p* *p'*, of projecting parts of the body *G* when the tool-stock is turned within the body, sufficient space being left between the opposing faces to admit the tool-stock to thus turn a short distance. 95 A sectoral block, *h*, is fitted to fill the space between the opposing faces at either end of the extended part *k*, being held in either position

of adjustment by means of a pin, *i*, extending out both ways from the opposing faces of the block and made to enter a hole, *o*, in the body. The block is of such a size as to hold the tool-stock, when the end of the part *h* is brought against it, in either position of adjustment, in such position that the tool *b* will stand parallel with the face of the apron, as shown in Fig. 2. In each case the block *h* is inserted in place nearer the point of the tool and forms a stop for the tool-stock, to prevent the tool being swung too far around by the work pressing against its point. The space at the other end of the part *h* allows the tool-stock to turn in the opposite direction for the purpose of carrying the tool away from the work when the latter starts back from the reverse motion of the planer. The tool is secured in place in the stock by means of a simple set-screw, *r*, as shown.

L represents the work, which, when moving in the direction indicated by the arrow in Fig. 2, is being acted upon by the tool, the block *h* serving to hold the tool in position, as stated. When the motion of the work is reversed, the tool will be carried slightly toward the dotted position (referred to by *l*) by the friction against its point, which tends to relieve the friction and allow the point of the tool to move easily along the work. This slight forward motion of relief for the point of the tool is rendered possible on account of the space between the faces *n* and *p*, above described. After the work, in its reverse motion, has passed the point of the tool, the latter is brought back in position for another cut by means of a spring, *t*, said spring, as shown, being an ordinary spiral spring secured at its respective ends to pins *s' s'*, projecting, respectively, from the under surface of the plate *H* and face of the body *G*. This light spring causes the tool to drag during the reverse motion of the planer, but only to the extent of the energy of the spring. To plane on the opposite side, a tool has to be put in the stock in an opposite direction, as shown in dotted lines, the block *h* transferred to the space at the other end of the part *h*, and the end of the spring that is attached to the pin *s'* changed to the pin *s''* on the other side of the block or body.

In using the device, the tool-stock is vertically adjusted within the body, and the point of the tool brought up to the work by means of the screw that moves the swinging slide *A* and the horizontal feed-works of the planer set in motion.

Fig. 3 shows the back surface of the body as being planed obliquely with the ends and bore receiving the tool-stock, so that the latter is held in an inclined position—that is to say, the upper end of the tool-stock inclines slightly away from the face of the vertical slide *A*. From this position of the parts it will be understood that when the said tool-stock is turned in its bearing within the body, as above stated, the point of the tool will not move in a hori-

zontal plane, but will deviate therefrom or move in an oblique plane and in such a manner that the said point will take a lower position as it moves away from its position when cutting on either side of the body—that is to say, the point of the tool will be lower when in the position shown at *l* than it will be when in the position shown at *b*. This dropping of the point of the tool assists in freeing it from the work, so that it will not drag when the work is running back.

In attaching my invention to the swinging slide of a planer, I do not confine myself to the use of the apron and clamping-bolts for the tool. This attachment may be formed to fit and be secured directly to the swinging slide, to partake of its vertical and oblique motions. It is well understood that the apron is hung at the top, so that it will swing out at the bottom for the purpose of relieving the point of the tool when the work is running back, in doing upper-surface planing. This motion of the apron, if the latter be used, needs to be prevented while doing under-surface work, for if it occurred it would cause the tool to catch onto the work and break when the latter started back. It will be easily understood that removing the apron entirely and clamping the attachment directly and rigidly to the swinging slide would be a proper and legitimate mode of attaching the same. If attached to the apron of the swinging slide, the former would have, by some simple means, to be secured rigidly to the latter, so that it could not rise therefrom.

I claim as my invention—

1. An attachment for an iron-planer, consisting, in combination with the swinging slide *A*, of a block, *G*, rigidly secured to the swinging slide, provided with a stock, *K*, for holding the cutter, said stock being fitted in a circular bearing within the block, for the purpose of permitting it to turn within the latter to bring the point of the tool in position to take a cut, or be turned to relieve the point of the tool from the work during the reverse motion of the planer, substantially as described.

2. An attachment for an iron-planer, consisting, in combination with the swinging slide, of a block, *G*, rigidly secured to the swinging slide, provided with a stock, *K*, for holding the cutter, fitted to a circular bearing within the block, for the purpose of permitting it to be turned within the latter at each forward and backward motion of the planer, to bring the point of the tool, respectively, in position to take a cut or relieve it from the work, said stock *K* being longitudinally adjustable within the block, substantially as described.

3. The attachment for iron-planers, consisting of a block, *G*, rigidly secured to the swinging slide *A*, stock *K*, for holding the cutter *b*, fitted to a circular bearing within the block *G*, for the purpose set forth, collar *H*, secured

to the stock K, and stop h, to limit the distance the stock may be turned within the block, substantially as set forth.

4. In combination with the swinging slide A of an iron-planer, a block, G, rigidly attached thereto, provided with a tool-stock, K, for holding the cutting-tool, said stock fitted to circular bearings within the block, for the purpose of permitting it to be turned therein to bring the point of the tool either to or away from the work, with automatic means to turn said stock in position to bring the point of the tool to the work, substantially as specified.

15 5. In combination with the swinging slide A of an iron-planer, a block, G, rigidly at-

tached thereto, provided with a tool-stock, K, for holding the cutting-tool, said tool-stock being fitted to a circular bearing within the block, for the purpose of permitting it to be turned therein to bring the point of the cutting-tool either to or away from the work, said tool-stock being held by the block in an inclined position, for the purpose of allowing the point of the tool to deviate from a horizontal plane when the stock K is turned in its bearings, as stated, for the purpose set forth.
